UNITED STATES PATENT OFFICE.

AUGUST G. SCHWIETERMAN, OF DAYTON, OHIO.

THERMAL MOTOR.

1,104,320.

Specification of Letters Patent. Patented July 21, 1914.

Application filed March 5, 1914. Serial No. 822,614.

To all whom it may concern:

Be it known that I, AUGUST G. SCHWIETERMAN, a citizen of the United States, residing at Dayton, in the county of Montgomery and State of Ohio, have invented certain new and useful Improvements in Thermal Motors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in thermal motors adapted to be actuated or influenced by the differences in atmospheric temperature.

20 The object of the invention is to provide a device of this type which is simple in construction and efficient in operation, and particularly adapted for winding clocks. It is to be understood, however, that its uses are not limited to that application alone, as the device is capable of furnishing power for other small or comparatively small objects.

Referring to the accompanying drawings illustrative of my invention, Figure 1 is a 30 rear elevation of a clock to which my improved thermal motor is applied; Fig. 2 is a side elevation of the same partially in section; Fig. 3 is a section on the line *a—a* of Fig. 1 showing the interior construction 35 of the motor; Fig. 4 is a section on the line *b—b* of Fig. 3; Fig. 5 is an enlarged detail sectional view of the return valve of the motor; Fig. 6 is an enlarged detail view of the motor piston; Fig. 7 is a vertical 40 sectional view through the winding drum; Fig. 8 is a detail view of the winding drum ratchet; and Fig. 9 is a detail view of the winding drum spring.

Throughout the specification and drawings, similar reference characters indicate corresponding parts.

Referring more particularly to the drawings, 1 represents a clock casing in which a clock 2 is mounted. The clock, in this instance, is provided with two key-spindles 3 which are each connected to a winding drum constructed as follows: Each winding drum consists of side plates 4 which are connected

by rods 5 which form a supporting frame. The supporting frame is attached to the back of the clock casing 1 by suitable brackets 6. Journaled in suitable bearings 7 in the plates 4 is a winding spindle 8 connected to its respective key-spindle 3 by a flexible coupling 9. Rigidly secured to said winding spindle 8 is a ratchet 10 adapted to be engaged by a pawl 11 mounted on a spool 12. The spool 12 is freely journaled on the spindle 8 and is under the influence of a spiral spring 13 one end of which is attached to the spool while the other end is attached to one of the plates 4. The spring 13 is adapted to rotate the spool 13 in one direction, while the said spool is rotated in the opposite direction by a weight 14 attached to a cord 15 which winds around the spool 12. Under the influence of the weight 14, the spool 12 is rotated to turn the key-spindle 3 through the agency of the coupling 9 and ratchet 10 to wind up the 70 clock. When the weight 14 is subsequently elevated, the cord 15 is wound upon the spool by the spring 13. The cords 15, there being one for each key-spindle 3, are provided with guides 16 which hold the weights 14 in a true vertical path. To elevate said weights 14 to permit them to subsequently wind the clock, the following thermal motor is provided.

Mounted in the base of the clock casing 85 1 is a cylinder 17 in which an inner piston cylinder 18 is mounted. Mounted in the cylinder 18 is a piston 19 provided with suitable packing 20. The piston 19 is attached to the lower end of a piston rod 21 which 90 extends upwardly through the cylinder 18 and through a packing gland 22. Mounted on the upper end of said piston rod 21 is a weighted cross-head 23 provided with anti-friction rollers 24 which roll on guides 25. 95 When the piston 19 is elevated in its cylinder 18, the cross-head 23 picks up the weights 14 and elevates them to a position where they may subsequently fall by gravity and to thus rewind the clock. The cylinder 100 18 is mounted in a plug 26 screw-threaded into the top of the cylinder 17. Above the top of said cylinder 17 is a cap 27 providing a reservoir with a packing gland 28 through which the cylinder 18 extends. The reservoir provided by the cap 27 communicates

with the interior of the chamber of the cylinder 17 at its bottom through a tube 29. The tube 29 is mounted in a plug 30 secured in the top of the cylinder 27. Said tube 29 is adapted to drain the reservoir 27 into the cylinder 17, and, in the lower end of said tube 29, a valve 31 is placed which is adapted to seat on a ring 32. The valve 31 is prevented from falling out of the tube by a head 33. The valve 31 is closed under the influence of pressure in the cylinder 17 by a flexible piston 34 mounted at the lower end thereof. The piston 34, however, being flexible, is adapted to permit of a flow of liquid 35 downwardly past the valve 31 and out of the tube 29. As appears in Fig. 1, the piston rod 21 is in its uppermost position, while Fig. 3 shows it in its lowermost position. In this latter position, the cross-head or weight 23 is immediately above the stuffing box 22. When said rod 21 is at its lowest point of travel and the temperature further lowers, a vacuum is created in chamber 17 which affects the valve 31 and opens the same and permits the liquid, a lubricant or oil 36, to flow back from the chamber in cap 27 to the bottom of chamber 17.

The piston 19 is elevated by the differences in temperature of the atmosphere or other medium in which the chamber 17 is placed through the agency of an expanding liquid 35, such as alcohol, in chamber 17, said liquid 35 having a high co-efficiency of expansion. The liquid 35, however, does not act directly upon the piston 19, but acts through the agency of the liquid 36 which is of higher specific gravity. The amount of liquid 36 is sufficient to more than fill the cylinder 18 when the piston 19 is at its greatest height. When the atmosphere in which the cylinder 17 is placed is at a low temperature, the liquid 35 will contract and will thus permit the weighted cross-head 23 to lower said piston 19. When the temperature is elevated, the liquid 35 expands and forces the liquid 36 into the cylinder 18 thereby elevating the piston 19, the cross-head 23 and the weights 14. To prevent the piston 19 moving to too great a height, the cylinder 18 is provided with a discharge port 37 in its upper portion which is uncovered by the piston 19. When this port 37 is thus uncovered by said piston, the liquid 36, acting under the expanding influence of the liquid 35, will flow into the reservoir 27 through the port 37. The liquid 36 will flow back into the bottom of chamber 17, when the liquid 35 contracts, through the tube 29 and pass the valve 31, the pressure on the piston 34 being relieved when the liquid 35 is contracting. When the liquid 35 subsequently expands, the valve 31 is closed by the piston 34 thereby preventing the liquid 36 flowing upwardly through

the tube 29. The amount of movement of the piston 19 will be in exact proportion to the varying temperature of the liquid 35 which receives its varying temperature from the atmosphere in which the motor is placed.

While in the drawings I have shown the device as applied to a clock having two key spindles and two weights 14, it is to be understood that the device is adapted to operate a clock having only one key spindle and one weight.

Having described my invention, I claim.

1. In a thermal motor, a cylinder containing a fluid susceptible of variations of expansion and contraction under varying atmospheric temperatures, a non-expansible fluid below said expansible fluid, and a tubular member projecting through said expansible fluid and into the non-expansible fluid, and a piston and rod within said tubular member and exposed to the action of the non-expansible fluid when the latter is affected by the expanding action effect of the expansible fluid.

2. In a thermal motor, the combination of an outer cylinder containing in its lower portion a non-expansible fluid such as a lubricating oil, and an expansible fluid thereabove, and a cap above said cylinder providing an upper chamber for a portion of said non-expansible fluid, a tubular member submerged in said non-expansible and expansible fluids and having a piston and piston rod affected by said expansible fluid through the action of the latter on the non-expansible fluid, said tubular member communicating with the upper non-expansible fluid chamber, and means affording a drainage of the non-expansible fluid from said upper chamber to the bottom of expansible fluid chamber, substantially as specified.

3. In a thermal motor, a cylinder having an upper and a lower chamber, a piston cylinder communicating with said upper and lower chambers, a piston in said last named cylinder adapted to be acted upon by liquid in the lower chamber, and a valve controlling the communication through said piston cylinder between said upper and lower chambers.

4. In a thermal motor, a main cylinder containing a fluid subject to expansion through changes in atmospheric temperature, and a non-expansible fluid below said expansible fluid, an overflow reservoir above said cylinder for said non-expansible fluid, a tubular member submerged in said expansible and non-expansible fluids, and having an overflow opening discharging into the reservoir for the non-expansible fluid, a piston and rod in said tubular member exposed to the action of the non-expansible fluid when acted upon by expansion of the

expansible fluid, a tubular member providing a communication between the non-expansible fluid reservoir and the portion of the main cylinder below the expansible fluid
5 contained therein, and a valve in said last named tubular member controlling said communication, substantially as specified.

In testimony whereof I affix my signature in presence of two witnesses.

AUGUST G. SCHWIETERMAN
